[57] ABSTRACT

A device for the suppression of reactions involving undue pressure rise in large-size containers having an explosive or thermo-chemically reacting contents, comprising a pressure sensor exposed to the internal pressure of the container controlling a pressure relieving device via two parallel-connected contact assemblies, one of the contact assemblies responding to the transgression of a predetermined value of the internal pressure of the container and the second contact assembly responding to the transgression of a predetermined pressure rise per unit of time.

SHEET 2 OF 2

DEVICE FOR THE SUPPRESSION OF REACTIONS INVOLVING UNDUE PRESSURE RISE IN LARGE-SIZE CONTAINERS

This invention relates to a device for the suppression of reactions involving undue pressure rise in large-size containers carrying explosive or thermo-chemical charges, comprising a pressure sensor and a pressure-relief unit controlled by the latter.

In the field of research technique, it is inevitable for explosive fuel-and-air mixtures to be produced in large size containers where the presence of sources of ignition cannot be safely excluded. The term "fuel-and-air mixture" also includes dust-and-air mixtures and gas or vapour-and-air mixtures. Unless the containers used for these mixtures offer adequate resistance to such pressures, this type of explosion may under certain circumstances cause substantial personal injuries and material damage and similar effects may result from thermo-chemical reactions going on in these containers although these reactions require a longer period of time for their build-up.

It is known that in the past, nascent explosions were occasionally suppressed by means of a device as hereabove described so as to reduce the effective range of the explosion and attenuate the expected blast pressure or the external pressure of the thermo-chemical reaction. The pressure feelers detect nascent reactions in time before they attain a really destructive force and will automatically release the pressure relief device which may either be a fire extinguisher, cooler or air-escape device as required. For example, in response to the pressure sensors suitable extinguishing fluids stored in appropriate tanks accommodated inside the large-size container under adequate pressure are introduced in the large-size container either by actuating quick-action opening valves or blowing off bursting plates, at a high discharge velocity. The success of the fire-extinguishing action is dependent not only on the type of extinguishing agent used, its storage pressure and the arrangement and number of fire-extinguisher containers, but primarily on the behaviour and sensitivity of repons of the pressure detectors who start the fire-fighting effort. With known devices for the suppression of explosions, the fire-fighting action starts when a predetermined minimum pressure of response, very low in comparison with the anticipated blast pressure, has been exceeded. Consequently, the risk of the fire-extinguishing system being released by mistake, such as by operational or occasional thrusts, is therefore, comparatively heavy. Erroneous releasing not only causes substantial material damage since the material stored inside the container becomes unfit for further use and the tanks for the fire-extinguishing means will also have to be refilled, but the also lead to interruptions of operation which may effect major departments as well. For the above reasons the known equipment appeared to be in need of improvement in several important respects.

It is the purpose of the present invention to improve upon a device of the type hereabove mentioned in such a manner as to make sure that fire-extinguishing or other pressure relieving actions will be started only following the actual occurrence of dangerous reactions. For that purpose, the pressure sensor is followed by two contact assemblies in parallel connection, of which the first releases an output signal when an input voltage

designating a predetermined pressure value has been exceeded, and the other when an input voltage denoting transgression of a predetermined rise of pressure per unit of time releases an output signal, the outputs of the contact assembly each being connected with an input of an AND-gate through which the pressure relief device can be released. The criterium for the evaluation of pressure rises inside the container not only takes pressure proper, but also the rise of pressure by unit of time into account. Therefore, the fire-extinguishing system and other equipment for the relief of pressure inside the container can be operated only if and when pressure and rise of pressure per unit of time simultaneously exceed certain limits. It is thus possible to eliminate the influence of operations accompanied by pressure fluctuations upon the releasing system of the device in such cases where the pressure pattern of these operations differs from the pressure pattern characteristic for explosive or thermo-chemical reactions. Thus erroneous releases as are liable to occur due to operational pressure variations, but also to external influences, such as concussion, lightning discharge and the like, can be safely precluded.

The selection of the limit values for container pressure and pressure rises per unit of time, whose simultaneous transgression would provoke a response from the pressure relief device, depends both on the composition and quality of the contents of the container and on the size of the container, as these data are of a decisive influence upon the determination of the pressure pattern in the event of an explosion. This pressure pattern is already known for various dust-and-air mixtures and certain container sizes and can be determined by trial and error if and when required.

Since the time available for the suppression of nascent explosions is extraordinarily short, it is absolutely necessary to make sure that the response of the contact assemblies will be practically instantaneous. According to another feature of the invention, the first contact assembly is an analog-to-digital converter and the second contact assembly is a differentiating circuit followed by an analog-to-digital converter by means of an amplifier, each of the two analog-to-digital converters consisting of a differential amplifier whose negative output is connected by means of a resistor to a voltage regulator fed by a reference voltage. By means of the voltage regulator the threshold of operation of the analog-to-digital converters can be altered and adapted to given requirements when necessary. In normal conditions, the outputs of the two analog-to-digital converters are set to the logical 1 voltage. The first analog-to-digital converter switches to logical 1 when the container pressure has exceeded the predetermined limit. The second analog-to-digital converter switches to logical 1 only when the output voltage of the differentiating circuit which is proportionate to the rise per unit of time of the container pressure, has exceeded the predetermined value. Only when logical 1 voltage is available at the outputs of both analog-to-digital converters, does the AND-gate transmit a signal for the release of the pressure relief device. At the same time, the output signal of the AND-gate can be used for the triggering of a monostable switch step followed by a pulse shaper releasing a rectangular pulse to be used after adequate amplification, for the release of a fire-extinguishing device or the like. For example, it may be that the release pulse fuses a filament as a result of which a valve opens through

which chemicals kept under pressure are blown into the container. By means of the same systems it is also possible to make an extinguisher powder burst.

According to another feature of the invention, the output and the negative input of each of the two differential amplifiers are fed back by means of a resistor. The purpose of this circuitry operation is to produce a hysteresis on the threshold of operation of the analog-to-digital converter, which means that although the analog-to-digital converter may be switched on as soon as the pressure has attained a certain level, the pressure then will have to fall slightly below this threshold, so as to make the analog-to-digital reverse again. This produces a clearly positive change-over precluding swinging about the conversion point at minor pressure variations.

According to another embodiment of the invention, the pressure sensor is made to follow a preamplifier preferably combined with it so as to produce a structural unit. This provides a possibility for producing a long cable connection between the measuring element and the rest of the electronic circuit.

According to the invention, other advantages can be obtained by introducing a low-pass filter between the pressure sensor and the two connecting assemblies. The low-pass filter serves to filter out undesirable frequencies and the area of operations of the device further narrowed as required.

Another embodiment of the invention comprises an additional circuit for the suppression of thermo-chemical reactions, comprising a monostable switch-step followed by a pulse sharper connected to the output of the first connecting assembly, a reversing stage connected to the output of the second connecting assembly and a bistable switch-step followed by a power amplifier, with the block input of the bistable switch-step being connected with the output of the pulse sharper, the preparatory input of the bistable switch-step with the output of the reversing stage, and the bistable switch-step being reset, if required, by means of a switch into the initial position. This additional circuitry makes it possible to detect and suppress also thermo-chemical reactions for which a relatively slow rise of pressure is characteristic and which are, therefore, located below the response limit of the second contact assembly. The output voltage of the additional circuitry can, for example, be used to actuate a relay controlling the aperture of air evacuation valves. In this way the container where in the thermo-chemical process takes place and which is unable to withstand the pressure to be expected, can be protected from damage and even destruction.

Further details of the invention will become apparent from the following description of the invention with reference to the accompanying drawings wherein.

FIG. 1 shows a diagram of the monitoring borders of a device according to the invention.

FIG. 2 the schematic diagram of the electronic sector of the device,

FIG. 3 a pressure sensor as part of the device according to the invention, and

FIG. 4 a variant of this pressure sensor.

Knowledge of the pattern of pressure developments inherent in explosions and other reactions involving rise of pressure is above all necessary for their suppression. These pressure developments per unit of time as may arise in view of different parameters in closed con-

tainers are shown in FIG. 1. The ordinate shows the container pressure P_{ex} on a logarithmic scale and the abscissa the time t also on a logarithmic scale. The diagram area is subdivided into monitoring areas I, II, and III defined by the releasing pressures adjustable within the limits of 0.05 to 0.5 atmospheres and the two pressure rise values P_{1ex} and P_{2ex} .

As a rule, pressure patterns coming within the monitoring area I should not produce and releasing functions in the device. The monitoring area I is subdivided into two sectors a and b , the sector a being limited against diminishing pressure gradients by grad P_{1ex} with 0.1 at/ μ s. This limitation results from the knowledge that larger gradients than 0.1 at/ μ s are safely precluded from occurring during explosions. However, if voltage patterns with gradients of that size occur at the input of the electronic circuit hereafter described in greater detail, they may be safely presumed to be caused by lightning strokes, atmospheric conditions or by mains interference.

In all of these cases, the release of any security measures in the device is undesirable. Curve A in the diagram stems from such an electronic interference signal simulating a pressure pattern in the diagram which is actually non-existent in the container.

The second sector b of the monitoring area I is that pressure range inside which operational pressure variations caused by example, by the opening and closing of flaps, throttles or valves or by alterations of the filling conditions or temperature, are normally located. Likewise, pressure variations corresponding to the curve B for example, should not release fire-extinguishing or other pressure-relieving measures either.

On the other hand, the monitoring area II comprises all pressure patterns that are characteristic for dust-and-gas explosions. The monitoring area II is defined by two constant pressure gradients P_{1ex} and P_{2ex} on the one hand, and by the releasing pressure adjustable within the range from 0.05 to 0.5. Curve C shows a typical pressure pattern for dust-and-gas explosions. Any pressure pattern arising inside area II must positively release the fire-extinguisher.

The monitoring area III covers the field wherein thermo-chemical reactions, such as for example, self-ignition of the contents of the container, occur. For these processes an initially slow and flat pressure rise is a characteristic feature. Only then will an explosion actually occur and the blast pressure valve proper superposes itself on the flat pressure rise. A curve pattern which is typical for thermo-chemical reactions of this kind is reproduced in curve D.

If the flat pressure rise exceeds the releasing pressure previously set, fire-extinguishers are actuated via a special channel or other measures are released to inhibit the nascent explosion. These combating measures depend on the type of plant to be protected. For example, with acid containers of a certain type, flushing valves will be actuated by electric ignition or ventilating flaps are opened in dust containers by electro-mechanical means. The limits for the area III are the pressure gradient P_{2ex} and the releasing pressure adjustable between the limits of 0.25 to 0.5 atmospheres.

The electronic circuit shown in FIG. 2 is used for the monitoring of the container pressure, classification of pressure variations if any, and also for releasing fire-extinguishing and other protective devices if required. The input of this circuit is a pressure transducer 1

which responds not only to pressure variations but also to the absolute value of pressure. It can be of the active or passive transducer variety, that is, capable of producing a voltage itself, such as for example, a quartz-type transducer or it can be fed by means of a source of power of its own, such as for example, a slide-wire bridge. The pressure transducer 1 is attached to the pressure container (not shown in the drawings) requiring monitoring and directly exposed to the pressure prevailing inside the container. Depending on the type and size of container used, one or more pressure transducers 1 will be provided.

The pressure transducer 1 is followed by a preamplifier 2 either attached to the pressure transducer 1 so as to form a single structural element, or located in the immediate vicinity of the pressure transducer 1 so as to provide a long cable connection, if necessary, for the following members of the circuit.

The pre-amplifier 2 is followed by a low-pass filter 3 by means of which electric interfering signals of the type of curve A in FIG. 1 liable to produce an erroneous release of the device, are suppressed.

The low-pass filter 3 is followed by an additional amplifier 4 whose output signal is proportional to that of the pressure transducer 1. After the amplifier 4 the circuit branches off into two branches, one of which is formed by a differentiating circuit 5 with an analog-to-digital converter 7 following same via an amplifier 6, and the other by an additional analog-to-digital converter 8.

The differentiating circuit 5 designated by symbols only comprises a condenser 9 followed by an operation amplifier 10 whose output and input are fed back via a resistor 11. The voltage at the output of the differentiating circuit 5 is proportional to the rise of the container pressure measured by means of the pressure transducer 1 with time, that is the value dp/dt . The output signal of the differentiating circuit 5 amplified in the amplifier 6 passes via an input resistor 12 to the positive input of a differential amplifier 13 whose output is connected with the positive amplifier input via a reaction resistor 14. The negative input of the differential amplifier 13 is via an input resistor 15 connected to the voltage regulator 16 fed by a reference voltage U_{ref} . The differential amplifier 13 in conjunction with the resistors 12, 14 and 15 provides the aforesaid analog-to-digital converter 7.

The second analog-to-digital converter 8 is of the same design as the converter 7 and the pressure-dependent voltage released by the amplifier 4 passes via the input resistor 17 to the positive input of the differential amplifier 18 belonging to the analog-to-digital converter 8 whose output is feedback-coupled with the positive input via a resistor 19. The negative input of the differential amplifier 18 also is connected via an input resistor 20 to a voltage regulator 21 which likewise lies at the reference voltage U_{ref} .

Each of the outputs of the two analog-to-digital converters 7 and 8 is connected to an input of an AND-gate 22 followed in series connection by a monostable switch step 23, a pulse shaper 24, a preamplifier 25 and finally a power amplifier 26. The output 27 of the power amplifier 26 leads to the pressure relieving device (not shown) designed either as a fire-extinguisher, cooling device or ventilator, as the case may be.

The section of the circuit so far described serves for the recognition of dangerous pressure patterns of an

explosive character comprised in the monitoring area II and for the release of adequate suppression measures. The area II is delimited by the appropriate adjustment of the threshold of operation of the analog-to-digital converters 7 and 8 by means of the voltage regulators 16 and 21. If the pressure-proportionate released by the amplifier 4 rises above the response value setting of the analog-to-digital converter 8, the analog-to-digital converter 8 whose output is normally at logical 0 voltage, is set to logical 1. In conformity with the above, the analog-to-digital converter 7, whose output is normally at logical 0 voltage, switches over to logical 1, if the voltage supplied by the amplifier 6 which is proportionate to the pressure rise per unit of time exceeds the response value setting. Thus a signal is produced at the output of the AND-gate 22 only if the two analog-to-digital converters issue logical 1 at the same time, that is, if in the container both the predetermined limits for pressure and pressure rise are exceeded at the same time, so that the criterium of the presence of an explosive action prevails.

The output signal of the AND-gate 22 triggers the monostable switch step 23 whose output pulse is transformed into a rectangular pulse in the following pulse shaper stage 24. The width of the rectangular pulse can be set as required in a manner known per se by means of the pulse shaper 24. The rectangular pulse amplified in the amplifiers 25 and 26 is of sufficient capacity to actuate the fire-extinguisher connected to the output 27 of the circuit.

For the control of dangerous thermo-chemical reactions inside the monitoring area III an additional circuit is provided. It consists of a monostable switch step 28 connected to the output of the analog-to-digital converter 8 and followed by a pulse shaper 29, a reversing stage 30 connected to the output of an analog-to-digital converter 7 and a bistable switch step 31 followed by a power amplifier 32 whose output is designated by reference number 33. The output of the pulse shaper 29 is connected with the clock input of the bistable switch step 31 and the output of the reversing stage 30 with the preparatory input of the bistable switch step 31. The bistable switch step 31 is moreover, reversible into its initial position by means of a switch 34.

The operation of this additional section of the circuit is as follows. When the reponse pressure setting (lower limit of the monitoring area III) has been exceeded, the logical signal arising at the output of the analog-to-digital converter 8 heads for the monostable switch step 28. The rectangular pulse then released by the pulse shaper 29 arrives at the bistable switch step 31. This is locked, however, when a logical 1 signal prevails at the output of the analog-to-digital converter 7 indicating that the limit for the pressure rise per unit of time has been exceeded. However, if the pressure rise in the container is only slow, that is of the type of pressure pattern of thermo-chemical reactions shown by curve D of FIG. 1, then a logical-0 signal prevails at the output of the analog-to-digital converter 7, so that the rectangular pulse arriving from the pulse shaper 29 reverses the bistable switch step 31. The output signal of the bistable switch step 31 adequately amplified by means of the power amplifier 32 will then release the safety device connected to the output 33. This may be a relay controlling the opening of air-evacuation valves on the container. The container is thus also protected

from damage or destruction by thermo-chemical reactions.

In order to ensure smooth operation of the whole device it is necessary to carefully calibrate its sensors and controls. This applies in particular to the pressure transducer 1 supplying the pressure data, whose sensitivity and efficiency must be subject to control any time.

FIG. 3 shows one of the possible arrangements of the pressure transducer by means of which the measuring efficiency of the unit can be checked any time. The pressure transducer 1 is connected with the large-size container 37 to be checked by means of a stop cock 39 located inside a connector 36. Between the stop cock 39 and the pressure transducer 1, a tubule 40 terminates in the connector 36 by means of which the pressure transducer 1 can, after closing the cock 39, be impinged upon by a reference pressure. The reference pressure emanates from a device not shown consisting of a pressure flask and a pressure-reducing valve. The reducing nozzles of this reference-pressure producer are so adjustable that both typical pressure patterns of dust or gas explosions and thermo-chemical reactions can be simulated. Upon completion of the checking operation, the tubule 40 for the reference pressure connection are closed and the stop cock is opened, so that the pressure transducer 1 again communicates with the large-size container 37 to be kept under surveillance.

Another possibility of checking the efficiency of the monitoring device as shown in FIG. 4 consists in the impingement of the inside of the transducer membrane by means of reduced pressure.

In that case it is possible for the transducer 1, whose housing also includes the pre-amplifier 35, to stay connected with the container 37 under control also during the checking operation. No stop cock is therefore necessary. The transducer 1 is provided with a tubule 41 by means of which the transducer membrane 38 can be impinged upon with underpressure. This underpressure is again supplied by an operation testing unit connected to the transducer to be checked by means of a hose. The size or time slope of the underpressure will be set in such a manner that it will produce at the transducer output designed as a connecting plug 42 the same signal as a gas explosion or a thermo-chemical reaction would. The transducer 1 is preferably attached to the wall of the large-size container by means of a clamp bolt 43 engaging a taphole of the container wall and pressing a front-face flange 44 of the transducer housing against a gasket 45 inserted in the receiving bore of the large-size container 37.

I claim :

1. A device for the suppression of reactions involving undue pressure rise in large-size containers with an explosive or thermo-chemically reacting contents, comprising at least one pressure sensor exposed to the internal pressure of the container and having an output delivering an electric signal corresponding to the internal pressure, two contact assemblies each having an input and an output, the inputs of the two contact assemblies being connected in parallel and connected with the output of the pressure sensor, the first of the

contact assemblies responding to an input voltage designating the transgression of a predetermined pressure value and releasing an output signal, the second contact assembly responding to an input voltage designating the transgression of a predetermined pressure increase per unit time and releasing an output signal, an AND-gate having two inputs and an output, the first of said inputs being connected to the output of the first contact assembly and the second input of the AND-gate connected with the output of the second contact assembly, a pressure-relieving device connected to the output of the AND-gate and releasable by means of the output pulses of the AND-gate.

2. A device according to claim 1, providing a first analog-to-digital converter forming the first contact assembly, a differentiating circuit having an output, an amplifier with an input and an output, the input of the amplifier being connected with the output of the differentiating circuit, a second analog-to-digital converter connected to the output of the amplifier, the differentiating circuit, the amplifier and the second analog-to-digital converter forming the second contact assembly, each of the two analog-to-digital converters comprising a differential amplifier having a positive input, a negative input and an output, a resistor preceding the negative input of the differential amplifier, a voltage regulator fed by means of a reference voltage, the negative inputs of both differential amplifiers being connected via the resistors to the voltage regulator.

3. A device according to claim 2, providing one reaction resistor each inserted between the positive input and the output of each of the differential amplifiers.

4. A device according to claim 1, providing a pre-amplifier inserted between the output of the pressure sensor and the parallel-connected inputs of the two contact assemblies.

5. A device according to claim 4, wherein the pressure sensor and the pre-amplifier are combined so as to constitute a common structural unit.

6. A device according to claim 4, providing a low-pass filter connected between the output of the said pre-amplifier and the parallel-connected inputs of the two contact assemblies.

7. A device according to claim 1, comprising an additional circuit for the suppression of thermo-chemical reactions, comprising a monostable switch step with an input and an output, the input of the monostable switch step being connected with the output of the first contact assembly, a pulse shaper with an input and an output, the input of the pulse shaper being connected with the output of the monostable switch step, a reversing stage with an input and an output, the input of the reversing stage being connected with the output of the second contact assembly, a bistable switch step having a clock input, a preparatory input, a resetting input and an output, the clock input of the bistable switch step being connected with the output of the pulse shaper, the preparatory input being connected to the output of the reversing stage and the resetting input connected with a switch for the resetting of the bistable switch step into the initial position.
